UNITED STATES PATENT OFFICE.

SAMUEL D. SIBLEY, OF SYRACUSE, NEW YORK, ASSIGNOR TO THE PNEUMELECTRIC MACHINE COMPANY, OF SYRACUSE, NEW YORK, A CORPORATION OF NEW YORK.

DOUBLE-COMPRESSION RECIPROCATING IMPLEMENT.

1,072,367.

Specification of Letters Patent.

Patented Sept. 2, 1913.

Application filed May 8, 1912. Serial No. 695,902.

To all whom it may concern:

Be it known that I, SAMUEL D. SIBLEY, a citizen of the United States, residing at Syracuse, in the county of Onondaga and 5 State of New York, have invented certain new and useful Improvements in Double-Compression Reciprocating Implements, of which the following is a specification.

The present invention relates to such pressure driven reciprocating implement that have two pistons, one driven by the other, and the object of my invention is to produce an implement of this kind that is simple in construction, has a short compression stroke 10 and variable striking positions. For this reason I provide a cylinder of two diameters, the most distinguishing feature of which is that it has no moving valves.

In the accompanying drawings:—Figure 20 1 is a longitudinal section of the working cylinder, with the parts shown in starting position; Fig. 2, a cross section on line 2—2 of Fig. 1; Figs. 3 and 4, longitudinal sections of the cylinder, with the pistons in section 25 and representing different stages of the stroke to what is shown in Fig. 1; Fig. 5 a cross section on line 5—5 of Fig. 1.

A, B, C, D represent the working cylinder or housing for pistons, compartment A, B 30 being of larger diameter than compartment C, D. In the following A, B will be referred to as the large compartment and C, D as the small compartment. A is the rear end and B the forward end of the large compartment 35 and C is the rear end and D the forward end of the smaller compartment of the working cylinder.

E is the driving piston for A B with a contracted portion extending into, and of 40 the same diameter as C D; through the motor driven piston rod H the driving piston receives its regular back and forth movement from a motor not shown. Packings T¹ T² T³ and T⁴ are suitably placed on the 45 driving piston to prevent leakage. The length of compartment A B is somewhat greater than the length of the stroke of the driving piston E in order to leave some play at the two extremities of the stroke between 50 the piston and the ends of the compartment A B.

F is the driven piston, with the tool rod G to which a bit (not shown) is attached at the forward end. In the side wall of the 55 working cylinder is an air passage P, open-

ing into the forward end D of compartment C D, through port P², a short distance from the end wall of compartment C D, so that when piston F strikes said end wall, it will close port P². The other port P¹ of 60 passage P opens into the rear end D of said compartment, and is so located that it will open into end B of compartment A B through passage M, only a moment after piston E has started on its forward movement. 65 The starting position is represented in Fig. 1 and shows the by-pass L in the piston E registering with port U, so that the compartment end B communicates with the open air. At the same time compartment end A connects with end C through passages N and 70 X in piston E and through port J, made as an annular groove in the side of the working cylinder. Near the end of the stroke of piston E, compartment end A 75 communicates with compartment end C through the same passages N, X registering with port K, cut in the side of the working cylinder. This is shown in Fig. 3. A step nearer the end of the stroke port Q, cut in 80 piston E, registers with port P¹, connecting ends B and C of the two cylinder compartments through passage P and port P². At the end of the stroke, the port S and the by-pass R, which are both situated in the driving piston E, at its large end, registers with the port U and the by-pass V, cut in the 85 side of the working cylinder, the port K is now closed by the piston E.

Proceeding now to describe the operation 90 of the tool we will consider seven different positions of the piston E as it makes a double stroke, moving with a uniform speed, actuated by a motor. In the first position, as represented in Fig. 1, piston F is standing just back of port P² having a cushion of air in front of it. Similarly piston E stands back a short distance from the rear end of compartment A B. As port U now is open, there will be atmospheric pressure 100 at end B; and practically the same pressure will be found at A, C and D, as A and C are communicating through N X J. In passing from the first to the second position ports J and U are closed and compartment 105 ends B and D communicate for a moment as port P¹ registers with by-pass M. Second position, when the large part E¹ of the driving piston has arrived to about the middle of compartment A B, all the passages are 110 116

now shut off, air is being compressed in ends B and C of the compartments and rarefaction is taking place at end A of compartment A B. This condition continues until 5 the driving piston E arrives in its third position, see Fig. 3, when the orifices of passages X register with port K allowing the air compressed at C in the compartment C D to pass over to A of compartment A B 10 through passages X N. A moment later, in the fourth position, the port P¹ opens through port Q so that the air compressed in end B of compartment A B is let through passage P and port P², opens into end D of 15 compartment C D. Piston F will then be retracted, partly actuated by compressed air in front of it and partly by suction behind it. As soon as piston F has passed the forward opening of port K it will close said 20 port, leaving an air cushion between the two pistons. At the end of the forward stroke of piston E, position 5, atmospheric air is let into end A of compartment A B through ports and passages S V R U, in order to 25 compensate for leakage; port K is closed but port P¹ remains open. On the return stroke of the driving piston all the ports are closed so that air will be compressed at end A and rarefied at end B of compartment A B. 30 Piston F continues its retracting movement following piston E until, in position 6, port P¹ opens through by-pass M into end B of compartment A B equalizing the pressure at B and D to a little below atmospheric. 35 In the next instant, position 7, port J is open, and the air compressed at end A of compartment A B rushes through passages N X into end C of compartment C D, reversing the movement of piston F, forcing 40 it forward, the driving piston E going back a little farther until it gets into its starting position, whereupon the operation is repeated. Should piston F on its forward stroke run past port P², no air can come 45 into end D of compartment C D, when the driving piston next returns to position 5. As a consequence piston F will not then be retracted. The whole machine will therefore have to be fed forward, preparatory to 50 the next stroke of the piston F so as to uncover port P², when the operation can again be repeated.

In the above description, it has been assumed that air was used as a pressure medium. I do not, however, limit myself to the use of atmospheric air, as any other pressure medium may equally well do the work.

In the claims chambers A and C are referred to as the rear ends and chambers B and D as the forward ends of the large and small compartment of the cylinder respectively.

I claim:—

65 1. A double-compression reciprocating

implement comprising a working cylinder having two communicating compartments of different diameter, in combination with a motor-driven piston working in both of said compartments and a tool-carrying piston 70 working in the small compartment only, said tool-carrying piston receiving its impulse through a pressure medium actuated by said motor-driven piston, said working cylinder and said motor-driven piston being 75 provided with means of communication for conducting the pressure medium, at successive predetermined parts of the stroke of the motor-driven piston, from the rear end of the small compartment to the rear end of 80 the large compartment; from the forward end of the large compartment to the forward end of the small compartment; from the rear end of the large compartment to the outer side of the cylinder; from the rear 85 end of the large compartment to the rear end of the small compartment; and from the front end of the large compartment to the outside of the cylinder, respectively, for the purpose of giving a reciprocating movement to the tool-carrying piston. 90

2. A double-compression reciprocating implement comprising a working cylinder having two communicating compartments of different diameter, in combination with a motor-driven piston working in both of 95 said compartments and a tool-carrying piston working in the small compartment only, said tool-carrying piston receiving its impulse through a pressure medium actuated by said motor-driven piston, a pressure fluid conduit in said working cylinder opening with its forward end near the front wall of the small compartment and the rear end of said conduit opening near the rear end 100 thereof; a port in said motor-driven piston connecting the rear opening of said conduit with the forward end of the large compartment at a certain part of the stroke, and another port in the same piston making similar 105 connection at a different part of the stroke; a second pressure fluid conduit in said motor-driven piston with one opening at the rear end, another opening around its periphery near the forward end of said motor-driven piston; a port in said working cylinder connecting said forward opening of the second conduit with the rear end of the small compartment at a certain part of the stroke, and another port in the cylinder 110 making similar connection at another part of the stroke; a third pressure fluid conduit in said working cylinder with its outer end communicating with a pressure fluid supply, and the inner end opening near the rear end 115 of the small compartment; a port in said motor-driven piston connecting the inner opening of the third conduit with the forward end of the large compartment at one part of the stroke, and another port in the 120

130

same piston connecting the inner opening of the third conduit with the rear end of the large compartment at another part of the stroke of said motor-driven piston.

- 5 3. A double-compression reciprocating implement comprising a working cylinder having one compartment of relatively large diameter and communicating therewith and in front thereof, a compartment of relatively 10 small diameter; in combination with a tool-carrying piston working in and being of the same diameter as the small compartment; its piston rod extending through the wall at the forward end of the small compartment; 15 a motor-driven piston, with its actuating piston rod extending through the wall at the rear end of the large compartment, the rear end of said motor-driven piston being of the same diameter as the large compartment and 20 the forward end thereof being of the same diameter as the forward compartment; pressure fluid conduits and ports in the working cylinder and pressure fluid conduits and ports in the motor-driven piston distributed; 25 one of said ports being situated at each end of said small compartment with one of said conduits connecting them, another of the ports located near the middle of the small

compartment, one of said ports being situated at the rear of the forward end of said motor driven piston, a plurality of said conduits running transversely through its forward end and another of said conduits opening at the rear end of the same piston, and connecting with said transverse conduits, as 35 well as an annular port near the rear end of the small chamber, whereby transmission of the pressure medium from one of said compartments to the other in both directions is accomplished; another of said ports at the 40 rear end, one near the forward end of said motor driven piston, one of said conduits near the front end of said large compartment and a port near the rear end of said small compartment whereby transmission 45 from the large compartment to the pressure fluid supply in both directions, all for the purpose of giving impulse in both directions to the tool-carrying pistons.

The foregoing specification signed at 50 Syracuse, New York, this 29th day of March, 1912.

SAMUEL D. SIBLEY.
